ABSTRACT: A pivoting gripper for a wire tying machine of the type which wraps wire from a coil around a package, twists the wire firmly to bind the package, and cuts the twisted wire from the coil. The pivoting gripper holds the free end of the wire from the coil during the twisting operation and includes a first and a second gripper jaw, each jaw having a face adapted to grip the free end of the wire. The first jaw is mounted in a gripper housing and moves alternately into and out of a gripper position with the second jaw intermediate the free end of the wire and the package. A pneumatic cylinder drives the first jaw into and out of the gripping position.

PIVOTING GRIPPER

BACKGROUND OF THE INVENTION

This invention relates to a wire tying machine and, in particular, to improved means in a wire tying machine for gripping the free end of a wire encircling a package.

There are currently numerous patents covering various types of wire tying machines, for example, U.S. Pat. No. 3,060,841 granted Oct. 30, 1962 to P. A. Vanderbilt; U.S. Pat. No. 3,179,038 granted Apr. 20, 1965 to T. B. Mackenzie and U.S. Pat. No. 3,251,296 granted May 17, 1966 to R. W. Smith. These wire tying machines are used to bind packages, bundles of newspapers and the like.

Typically, in such a machine the package to be tied is moved along a conveyor onto a platform of the machine. A wire strand from a coil is then made to encircle the package with parallel runs of the wire loop or strand passing beneath the platform under the package. The free end of the wire is then gripped by means for gripping and the wire is securely tightened around the package. Next, twister means twist parallel runs of the wire together. The means for gripping then releases the free end of the wire while the end of the wire attached to the coil is severed. The bundle or package then advances, and the next bundle or package is positioned on the wire tying machine.

Typically the means for gripping the free end of the wire loop or strand includes a pair of jaws which mate to securely grasp the free end. One of these jaws is normally positioned between the free end of the wire loop and the package. This, however, has resulted in a problem. Since the jaw remains in an intermediate position between the free end and the package, it holds the free end of the wire away from the package. Thus after the twister twists the parallel runs together and disengages from the twisted wire permitting it to snap tightly around the package, the free end of the wire catches on the gripper jaw and is bent away from the package. This outwardly bent end clogs machines and damages packages and bundles. It also creates a source of injury to those handling the packages or bundles. In short, prior art gripper means are not entirely satisfactory.

SUMMARY OF THE INVENTION

In a principal aspect, the present invention comprises an improved means for gripping the free end of a wire which is being twisted about a package by a wire tying machine. Included in the means for gripping is a gripper jaw positioned between the wire end and the package. The jaw is adapted to pivot and allow the free end of the wire to be released by the gripper means and thereby snap cleanly against the package or bundle after the wire is twisted by the twister means and the twister means disengage the twisted wire.

It is thus an object of the present invention to provide an improved wire tying machine.

It is a further object of the present invention to provide improved means for gripping the free end of wire in a wire tying machine.

Still another object of the present invention is to provide a pivoting jaw included with the means for gripping which can easily be synchronized with the operation of the twisting means of the wire tying machine.

A further object of the present invention is to provide an improved means for gripping which may be easily incorporated with presently designed and manufactured wire tying machines.

These and other objects, advantages and features of the present invention will be more fully set forth in the detailed description which follows:

BRIEF DESCRIPTION OF THE DRAWINGS

In the detailed description which follows, reference will be made to the drawings comprised of the following FIGS.:

FIG. 1 is a front view of the improved means for gripping in gripping position;

FIG. 2 is also a front view of the improved means for gripping with the gripper jaws withdrawn from a gripping position;

FIG. 3 is an exploded view of the invention of the improved means for gripping; and

FIG. 4 is a perspective view of the improvement illustrated in FIG. 3.

DESCRIPTION OF THE PREFERRED EMBODIMENT

While the preferred embodiment of this invention is described in relation to a wire tying device of the type disclosed in the Smith patent, previously cited, embodiments of the invention may be used with any similar wire tying device.

Further, because wire tying machines, such as disclosed by Smith, are well known in the art, the entire wire tying machine is not shown in the drawings. Rather the drawings illustrate the improvement which is the invention.

Referring to FIGS. 1 and 2, typically in a wire tying machine a package 10 is positioned in the machine so that a loop or strand of wire 12 unwinding from a coil 14 may be passed under and around the package 10. The strand 12 of wire thus makes two parallel runs beneath the package 10 with one run terminating as a free end 16 and the other end extending to the coil 14.

The free end 16 is then grasped between gripper means 17 and the wire from the coil 14 is tightened about the package 10. Twister means 18 then engage the parallel runs of wire beneath the package 10 and twist those runs together. While the twisting operation takes place, the free end 16 of the wire is maintained in a gripped position.

After twisting the parallel runs, the twister means 18 retracts permitting the twisted wire runs 20 to snap tightly against the package 10. Simultaneously the gripper means 17 releases the free end 16 of the wire. In prior art devices this release was not entirely effective because a part of the gripper means 17 would remain between or intermediate the free end 16 of the wire and the package 10 causing the free end 16 to bend away from the package after being released by the twister 18. The present invention provides gripper means 17 which moves completely out of the path of the wire end 16 permitting the end 16 to snap cleanly against the package 10 along with the remainder of the twisted strand or loop 12.

FIGS. 3 and 4 illustrate in greater detail the improved gripper means. Included is an upper gripper jaw 22 having a gripper face 24, a lower gripper jaw 26 having a gripper face 28 and a gripper housing 30. The upper gripper jaw 22 includes an extended mounting arm 32 which is adapted to slidably engage a slot 34 in housing 30. Arm 32 is pivotally mounted in slot 34 by means of a shoulder screw 36.

Threadably inserted in a screw opening 38 in the head of upper gripper jaw 22 is an eyepin 40. A pneumatic cylinder 42 having an extendable piston rod 44 attached to a bracket 46 is connected with the eyepin 40. The opposite end of the cylinder 42 is pivotally mounted in a fixed block 48. Block 48 is, in turn, attached to a gripper housing platform 50. Thus, when piston rod 44 withdraws within cylinder 42, the upper jaw 22 rotates about the axis of shoulder screw 36 and is withdrawn from a position where jaw 22 may cooperate with jaw 26. Extending the piston rod 44 from cylinder 42 drives the jaw 22 into a position where it can cooperate lower jaw 26.

Lower jaw 26 is slidably positioned in a vertical channel 52 defined in the housing 30. Lower jaw 26 is normally biased in a retracted gripper position by a spring 54 cooperating with a washer and pin 58. A jaw extension 60 of the jaw 26 engages an integral forward crossmember 62 of housing 30 which also serves to define part of the vertical channel 52.

A plate 64 attached to housing 30 by means of machine screws 66 and 67 prevents lower jaw 26 from becoming disengaged from the channel 52. The plate 64 includes an upper wire guide surface 70 which guides the incoming run of an end of wire from a coil as the wire is being passed about a package in the wire tying machine. Thus, in operation wire from a coil

as at 14 in FIGS. 1 and 2 passes under the package 10 is guided over the surface 70 of the plate 64, passes upwardly around the package 10 and back down and under the package 10.

The end 16 of the wire then passes between the gripper jaws 22 and 26 and more particularly between surfaces 24 of jaw 22 and 28 of jaw 26. At this point upper gripper jaw has been rotated in the direction of the arrow in FIG. 4 so as to be appropriately in position to engage the end 16 of the wire in cooperation with lower jaw 26. Lower jaw 26 is then driven upward against the force of the spring 54. The means for driving the lower jaw 26 upward are well known in the art and therefore not illustrated. The end 16 of the wire is engaged between the jaws and the coil 14 is reversed so as to tightly draw the strand 12 about the package 10. The twister means then advances into engagement with the parallel runs of wire beneath the package 10 and twist these runs in the manner previously described.

The twister means then retracts from engagement with the twisted wire. Simultaneously, the upper jaw 22 is withdrawn from engagement with the end 16 of the wire in response to the action of the cylinder 42 in the direction opposite that of the arrow shown in FIG. 4. At the same time, of course, the lower jaw 26 retracts to the position illustrated in FIG. 4 which is limited by the jaw extension 60 and crossmember 62. The sequence of operation is then repeated for the next package which enters the wire tying machine.

Although a single pair of jaws have been illustrated for gripping the end of a wire strand, the present invention is operable to provide similar results with any arrangement of gripper jaws. The important feature of the invention is the removal of the jaw or any portion of a jaw from a position intermediate the end of the wire strand and the package subsequent to the twisting operation. This eliminates the problem of bending an end of the wire away from the package.

I claim:

1. In a wire tying machine of the type which passes a wire

loop around a package on a platform, said wire having opposite ends which make parallel runs, at least one of said ends being free, said machine including twister means to twist said wires together, the improvement comprising in combination:

means for gripping said free end of wire, said means including at least two jaws;

one of said jaws being a lower jaw substantially perpendicular to said parallel runs of wire;

the other of said jaws being an intermediate jaw pivotally mounted in a plane substantially parallel to said parallel runs of wire and movable between a retracted position and a gripping position, said intermediate jaw being intermediate said package and said free end of wire when in said gripping position;

said intermediate jaw cooperable with said lower jaw for gripping said free end of wire in said gripping position; and

driving means for pivotally moving said intermediate jaw between said gripping position and said retracted position.

2. The improvement in claim 1 wherein said driving means include a pressure responsive cylinder pivotally connected to said intermediate jaw.

3. In a wire tying machine of the type which passes a wire

loop around a package on a platform, said wire having opposite ends which make parallel runs, at least one of said ends being free, said machine including twister means to twist said wires together, the improvement comprising, in combination:

means for gripping said free wire end, said means including at least two jaws, one of said jaws positioned intermediate said package and said free wire end while said free wire end is being gripped between said intermediate jaw and the other jaw, means for removing said intermediate jaw from position between said package and said free wire end, said means for

removing including driving means, said driving means including a pressure responsive cylinder pivotally connected at one end to said intermediate jaw and fixed at its opposite end.
